UNITED STATES PATENT OFFICE.

HEYE J. WESSELS, OF GERMAN VALLEY, ILLINOIS.

RAILWAY-TIE.

972,303.

Specification of Letters Patent. Patented Oct. 11, 1910.

Application filed March 31, 1910. Serial No. 552,617.

To all whom it may concern:

Be it known that I, HEYE J. WESSELS, a citizen of the United States, residing at German Valley, in the county of Stephenson, 5 State of Illinois, have invented certain new and useful Improvements in Railway-Ties; and I do hereby declare the following to be a full, clear, and exact description of the invention, such as will enable others skilled in 10 the art to which it appertains to make and use the same.

This invention relates to railway ties.

The object of the invention resides in the construction of a railway tie which comprises 15 a pair of similar cementitious sleepers connected together by a tie member and which will be exceedingly durable, efficient in use and comparatively inexpensive to install and maintain.

With the above and other objects in view the invention consists in the details of construction and in the arrangement and combination of parts to be hereinafter more 20 fully described and particularly pointed out in the claims.

In describing the invention in detail reference will be had to the accompanying drawings wherein like characters of reference denote corresponding parts in the several views, and in which,

Figure 1 is a side elevation of a railway tie, partially in section, constructed in accordance with the invention; Fig. 2, a detail perspective view of one of the sleepers 30 with the metallic rim surrounding the same removed; and, Fig. 3, a detail fragmental view of one of the metallic rims which surrounds the sleeper, showing the connection between said rim and the tie member.

Referring to the drawings, the tie is shown 40 as comprising a pair of cementitious sleepers A and B connected together in the proper relation by a tie member C. As the sleepers A and B are identical in every respect, only 45 the sleeper A will be referred to in detail, the same being shown as comprising a cementitious core 5 which is reinforced for strength by wires 6 in the usual manner.

The upper face of said core 5 is formed with 50 a groove 6' for the reception of the base of

the rail. Molded into the core 5 is one end of the tie member C which in this instance is shown as having the form of a squared pipe and is so positioned within the core that the upper side thereof is substantially 55 in the same plane as the base of the groove 6; said upper side being provided with apertures 7 for the reception of spikes 8 which serve to secure the rail to the sleeper. The interior of the tie member C is filled 60 with a mass of twisted wire 9 which is adapted to be gripped by the engaging end of the spikes 8 to effectually secure the rail against displacement. The sides of the tie member C are slit at their ends to form 65 tongues 10 which are bent laterally against the cylindrical face of the core 5. The core 5 is protected against injury by a metallic rim 11 which surrounds the same and has its upper and lower edges crimped over the 70 upper and lower face of the core to positively secure the latter within said rim. The metallic rim 11 is positively secured to the tongues 10 by means of rivets 12 which add to the general strength and compactness of 75 the tie.

What is claimed is:

1. A railway tie comprising two separate cement sleepers, and a tubular tie member connecting same and having its terminals 80 respectively embedded therein, said tie member being provided with apertures adapted to receive the rail securing spikes and a spike securing filling disposed within said member.

2. A railway tie comprising two separate 85 cement sleepers, a metallic rim disposed around each sleeper and a tubular tie member connecting the same and projecting through the sleepers at its respective terminals, the said tie member having its projecting ends slit longitudinally to form tongues adapted to be bent outwardly and secured against the inner face of the metallic rim disposed around the sleeper.

In testimony whereof, I affix my signature, in presence of two witnesses.

HEYE J. WESSELS.
